UNITED STATES PATENT OFFICE.

WILLIAM J. KENELY, OF ELIZABETH, NEW JERSEY.

HEATING-FLUE.

1,073,351.

Specification of Letters Patent. Patented Sept. 16, 1913.

Application filed October 10, 1912. Serial No. 724,900.

To all whom it may concern:

Be it known that I, WILLIAM J. KENELY, a citizen of the United States, residing at Elizabeth, in the county of Union and State of New Jersey, have invented certain Improvements in Heating-Flues, of which the following is a specification.

This invention relates to heating flues for chimneys of dwelling houses and the like, and the objects of the invention are to provide a flue branching from the chimney off through a room and back again to the chimney, by which the heat of the escaping gases may be utilized to warm said room; to provide branch flue sections or boxes which can be incorporated in a chimney during its course of construction and to which sections or boxes the said flues can be supplied at any subsequent time; to provide for a plurality of flues at the same floor or level; to provide suitable dampers or valves whereby the gases may be directed as desired and the draft of the fire preserved; to secure simplicity of construction and installation, and to obtain other advantages and results as may be brought out in the following description.

Referring to the accompanying drawings, in which like numerals of reference indicate the same parts throughout the several views, Figure 1 is an elevation, partly in section, of my device as applied to a chimney, and Fig. 2 is a perspective view of a portion of a room illustrating that portion of the chimney to which the heating flue is applied.

In the specific embodiment of the invention illustrated in said drawings, 1 indicates the wall into which the chimney 2 is built as customary, the said chimney being shown as rectangular in cross section. It is to be understood, however, that the invention is equally applicable to chimneys of other cross sections and that I do not wish to limit the scope of my patent to any particular design of chimney. Preferably near the floor is incorporated into the chimney a heat-flue section 3, the same being preferably composed of some material which is readily molded into the desired shape, as cement. Said section 3 is hollow and conforms substantially to the chimney, so as to form a longitudinal portion thereof having the usual characteristics of the rest of the chimney. Projecting laterally from two opposite vertical faces of said section 3 are tubular connections 4, 4

adapted to receive the ends of the heating flues 5, 5. The said connections 4, 4 provide within themselves horizontal passages 6, 6 opening within the section 3 into the central vertical passage 7 which is a part of and preferably in alinement with the main passage 8 of the chimney 2. It will be understood that the said tubular connections 4, 4 project from the chimney into rooms on opposite sides of the chimney, and that there might be only one such connection, or more than two, according as the rooms are located. I have shown two in the drawing, for purposes of illustration. Near the top of the room the chimney is provided with a section 9 having lateral tubular connections 10, 10 similar to those of the section 3 already described, and in alinement therewith. A heat flue 5 is then placed in each room, having a middle and preferably upright body portion 12 and laterally bent and squared ends 13, 13 one adapted to telescope onto the tubular connection 4 at the lower part of the room and the other to similarly connect with the tubular connection 10 at the top of the room. A branch or shunt flue is thus provided, lying wholly within the room, through which the gaseous products of combustion can be directed instead of through the chimney proper, if desired, as will next be described.

In order to direct and control the flow of gases from the lower heat-flue section 3 into the heating flue 5, I provide in said section dampers or valves, one such damper 14 being adapted to close the vertical passage 7 of the section, and two other dampers 15, 15 being arranged to open or close the horizontal passages 6, 6, when so desired. The damper 14 comprises a sheet or plate of metal 16 adapted to lie in closed position upon a ledge 17 projecting from the interior walls of the section passage, a hinge rod 18 being secured in fixed position to said sheet or plate near one edge thereof and preferably at its upper side, as shown, to swing the same. This rod 18 in the construction shown extends through the wall of the section 3, so as to project into both rooms, and has at each end a laterally bent or projecting handle 19 by which said rod can be turned to swing the sheet or plate 16 into either open or closed position, as will be understood. Obviously, in the case of a single room, instead of rooms on opposite

sides of the chimney, there would be only one projecting and handled end of the hinge rod.

Each of the dampers 15 comprises a sheet or plate 20 of metal or other suitable material, which is arranged transversely of the passage 6 and provided near one edge of itself with a hinged rod 21 secured flatwise thereto and projecting at one end through the tubular connection 4 to form a handle for turning, said handle 22 being preferably bent laterally. A flange or web 23 projects from the inner side of the passage 6 for the damper to close against, and although this flange or web is shown inside the damper plate 20, it might obviously be placed on the outer side if preferred.

If no heat is desired in a room where one of the heat-flues is located, the damper 14 is tipped up into vertical position, or to be more exact leaning against the side wall of the section passage so as to retain its position, and the damper 15 in the heat-flue connection is closed or likewise tipped into upright position so as to lean against the web or flange 23. However, if heat is wanted in the room, the damper 14 in the section 3 is tipped downward or closed, as shown in the drawing, and the damper 15 in the heat flue connection 6 is also tipped down or opened as shown in full lines. The heat now cannot pass straight up through the chimney, but will be directed around through the heat-flue 5 to warm the room.

The flue 5 is of course preferably made of sheet-metal or other material adapted to readily transmit heat by conductivity to the surrounding end.

The upper flue section 9 has dampers 24, 24 in its tubular connections 10, 10 and in its main upright passage 25 it has a damper 26 similar to the one already described in connection with the lower heat-flue section 3, except that this damper 26 lies in closed position across the passage of the section upon a ledge 27 beneath the tubular connections 10, 10. It will be understood that the dampers in the upper flue-section 9 are to be operated in a manner similar to those already described in connection with the lower flue section 3, and simultaneously therewith. There is thus no chance for back draft or for flow of the gases in any direction except straight up the chimney when

the dampers are arranged therefor or around 55 through the flue 5 when the dampers are arranged for that.

By my invention I thus provide means for cheaply and conveniently warming a room adjacent to a chimney by utilizing the heat 60 of the gases and products of combustion passing upward therethrough and which heat would otherwise be wasted.

Having thus described the invention, what I claim is—

1. The combination with a chimney having upper and lower sections, each providing a lateral tubular connection, dampers in the main passages of said sections, and dampers in the said tubular connections of 70 a heat-flue extending between said tubular connections outside the chimney.

2. The combination in a chimney having an interior longitudinal passage, of upper and lower sections each having a lateral 75 projection, a damper in each of said projections, a damper in the interior longitudinal passage of the upper section immediately below the opening of the lateral projection thereof into said longitudinal passage, and a damper in the interior longitudinal passage of said lower section immediately above the opening of its lateral projection into said longitudinal passage, whereby gases ascending through the longitudinal passage may be deflected into the lateral openings as desired.

3. The combination in a chimney having an interior longitudinal passage, of upper and lower sections each having a lateral 90 projection, a flue detachably affixed at its opposite ends to said projections, a damper in each of said projections, a damper in the interior longitudinal passage of the upper section immediately below the opening of 95 the projection thereof into said longitudinal passage, and a damper in the interior longitudinal passage of said lower section immediately above the opening of its lateral projection into said longitudinal passage, 100 whereby gases ascending through the longitudinal passage may be deflected into the lateral openings as desired and carried through the said flue to the upper section.

WILLIAM J. KENELY.

HOWARD P. KING,
MILDRED E. BROOKS.
